UNITED STATES PATENT OFFICE.

ARCHIBALD EDWARD FORD, OF LONDON, ENGLAND.

COLLAPSIBLE BOAT.

1,303,550.

Specification of Letters Patent. Patented May 13, 1919.

Application filed June 10, 1918. Serial No. 239,229.

To all whom it may concern:

Be it known that I, ARCHIBALD EDWARD FORD, a subject of the King of Great Britain, residing at 42 North Audley street, London, England, have invented certain new and useful Improvements in and Relating to Collapsible Boats, of which the following is a specification.

This invention comprises improvements in 10 and relating to collapsible boats, and has for its object to provide craft of this type which are not expensive to produce, which are easily made ready for use or collapsed, and when in the collapsed condition occupy 15 a minimum of space, and which possess great stiffness and stability having regard to the fragile nature of their construction.

It has already been proposed to construct collapsible boats with a rigid keel provided 20 with a stem and stern post integral with or hinged to the keel, flexible longitudinal ribs or stiffeners and gunwales hinged to the said stem and stern post, a single or double skin or envelop permanently fixed by nails or 25 otherwise to the keel, stem, stern post and longitudinal stiffeners and means such as stretchers or floors and struts for maintaining the longitudinal ribs or stiffeners in the distended or erected condition, such struts 30 having been in some cases used with chains or the like for preventing undue distention of the longitudinal ribs or stiffeners. Collapsible boats have also been made unsinkable by providing buoyancy chambers comprising a flexible jacket or outer cover 35 furnished with an inner pneumatic tube and extending along each side and outside of the boat's skin or envelop and such boats have also been provided with a covering or 40 tension of the skin at each end like a half deck.

According to this invention the skin or hull is of fabric or other suitable material which is stretched by longitudinal canes, 45 stiffeners or the like all connected or tied together at their ends instead of being connected to a stem and stern post. Two of these stiffeners form the gunwales and others are situated at the floor level and immediately also if desired, the side stiffeners being maintained at the desired lateral distance apart by means of transverse stretchers, some of which are pivotally mounted beneath the floor boards or foot boards, 50 spreading being prevented by cross tie cords 55

which are pulled to give the desired tension and then knotted. The sides are preferably erected and stiffened by cross diagonal struts engaged with the upper and lower longitudinal canes or stiffeners, these struts 60 being adjusted and held in position by tie cords. In order to keep the upper and lower stiffeners in their proper relative positions, struts are provided between them. If desired the sides of the boat may be further 65 stiffened by the employment of inclined struts mounted between and engaging the gunwale or the upper longitudinal stiffeners and the transverse stretchers.

Further objects and advantages of this 70 invention will appear in the following description and the novel features will be particularly pointed out in the appended claims.

And in order that this invention may be 75 readily understood reference is made to the accompanying drawings in which:—

Figure 1 is a longitudinal section of a collapsible boat constructed according to this invention and 80

Fig. 2 is a plan of same.

Fig. 3 is a transverse section on the line III—III of Fig. 1 and

Fig. 4 is a similar view on the line IV—IV Fig. 1.

Fig. 5 is a part plan of a modified construction of stretcher and flooring and

Fig. 6 is a transverse section of same.

Fig. 7 is a plan of a modified construction of collapsible boat and 90

Fig. 8 is a side view of same.

Fig. 9 is a transverse section on the line IX—IX of Fig. 7.

Fig. 10 is a vertical section showing means for stepping a light mast on the foot board. 95

Fig. 11 is a transverse section of a modified arrangement for stepping the mast.

Fig. 12 shows another construction for stepping the mast and

Fig. 13 is a plan of same. 100

Fig. 14 is an inverted plan view of a folding foot board.

Fig. 15 is a longitudinal section of part of another construction of collapsible boat with a keel and keel stiffener and 105

Fig. 16 is a transverse section on the line XVI—XVI of Fig. 15.

Fig. 17 is a detail side elevation of a modification of the means for holding the keel stiffener in position and 110

Fig. 18 is a transverse section thereof and Fig. 19 is an enlarged vertical section showing means of securing the ends of the side rods or stiffeners.

- 5 The improved boat comprises, as shown in Figs. 1 2 and 3 of the drawings, a skin or hull made of waterproofed canvas or other suitable material *a*, the gunwales *b* being stiffened by means of rods or stiffeners *c*
 10 10 which may be of bamboo or cane, conveniently inserted in tubular edges or pockets *d* formed along such gunwales and joined together at or near each of their ends by a cord *z* or the like passing through trans-
 15 verse perforations in the said stiffeners. The skin *a* extends over the top to form a kind of half deck at each end of the boat and this moreover provides a kind of pocket to contain and retain the ends of the longitudinal stiffeners.
 20 The bottom *a*¹ of the boat is furthermore shaped and stiffened by means of lower longitudinal stiffeners or rods *c*¹ which may also be made of bamboo or cane and which may differ from the gunwale stiffeners or rods *c* in shape or curvature, when the boat is in the erected condition, chiefly owing to the upward bending thereof as shown at *c*² for the purpose of suiting the respective shapes of the prow and stern. It
 25 is convenient to make small boats with the two ends similarly shaped, in which case the stiffeners or rods would be similarly flexed or bent at both ends.

The sides of the boat are erected and stiffened chiefly by means of cross diagonal struts *e*, one pair being used near the forward end and another pair at the stern end. These two pairs are usually found sufficient for small boats and are preferably pivoted
 30 together in the middle where they intersect. These diagonal struts *e* engage the upper stiffener *c* on one side and with the lower stiffener *c*¹ on the opposite side. If desired, for longer boats the sides may be further stiffened or shaped by a third stiffener marked *c*³ between the upper and lower stiffeners *c* and *c*¹. Near each end of the boat the upper stiffeners *c* and the upper ends of the struts *e* are connected together by means
 35 of cords or ties *h* which are suitably tensioned whereby the crossed diagonal struts *e* are held in place and the upper ends are prevented from spreading.

The lower rods or longitudinal stiffeners *c*¹ are preferably spaced apart by means of a series of three or more transverse stretchers or floors *f* pivotally mounted at *f*¹ upon the under side of the burdens or foot-board *g*. If desired the foot board may be divided
 40 and hinged in the middle of its length at *g*¹ so as to occupy less space longitudinally when the boat is in the folded condition. The stretcher or floor *f*, situated at this place is not necessarily pivoted to the foot
 45 board and in that case is placed in position

first. By placing the foot board in the bottom of the boat and turning the stretchers *f* (pivoted to the foot board) into position at right angles to the keel line of the boat, the ends *f*² of these stretchers *f* being furnished with recesses corresponding to the contour of the stiffeners *c*¹ engage the lower stiffeners *c*¹ and hold them apart at the required distance. These stiffeners *c*¹ are maintained in engagement with the transverse stretchers or floors *f* and are prevented from spreading preferably by means of cross ties in the shape of ties or cords *h*¹ which are adjusted and then tied and knotted so that, when the transverse stretchers *f* are forced or tapped into position, the cross ties *h*¹ are tensioned and hold the parts in engagement.

In order to stiffen the sides when erected and as shown in Figs. 1, 2 and 3 inclined struts, stiffeners or stretchers *l* may be advantageously inserted between the upper and lower longitudinal stiffeners *c*¹ on the same side, the ends of these struts *l*, being suitably shaped or fitted for engaging the said stiffeners *c*¹. The pockets *d* are partially interrupted or opened at these places to permit the upright struts to engage with the longitudinal stiffeners. If desired, vertical tubular pockets may be formed upon the interior of the sides of the boat to receive these upright struts or stiffeners. Or fabric caps may be formed near the gunwale *b* to receive the upper ends of these stiffeners *l*.

As shown in Fig. 4 to further stiffen the sides of the boat struts *l*¹ inclined to the struts *l* may be employed in the waist of the boat or amidships, the lower ends of the said struts being adapted to engage in notches *F*¹ in the stretchers *f*, while their upper ends are recessed and adapted to engage with the upper stiffeners *c*. Or instead of being jammed against the stiffeners *c* the upper ends of the inclined struts *l*¹ may be received in pockets formed in or on the tubular pockets for the stiffeners *c*.

As shown in Figs. 5 and 6, the transverse stretchers *f* are suitably secured in place on the stiffeners *c*¹ by means of cleats *c*⁴ *c*⁵, over which the recessed ends of the stretchers are sprung. The cleats may also be used to keep any of the struts herein described in position. The burdens or foot boards may be wholly or partially made of slats *g*² *g*³ connected together by battens (not shown) and the slats may be held in position by means of clips *g*⁴ hinged or pivoted to the stretchers *f*. In this case the stretchers are not pivoted to the foot boards and when the latter are dropped in place, the clips *g*⁴ are rotated or turned so as to lie fore-and-aft between the slats *g*² and *g*³, after which they are turned to the position shown so as to engage with the slats *g*².

In order to increase the stability and

buoyancy of such a craft and as shown in Figs. 7, 8 and 9, the fabric skin or body *a* is formed or provided with known external longitudinal tubes or pockets *i* which may 5 be inflated or filled with buoyant material. Or as shown inflatable tubes *k* fitted with valves *k*¹ may be inserted in the said pockets *i* as will be readily understood. As will be 10 seen, such buoyant belts not only increase stability and buoyancy but they also act as fenders.

The foot board *g* may be provided as shown in Fig. 10 with a socket *s* for enabling a light mast *t* to be stepped, and such socket 15 may be hinged at *s*¹ to lugs on a plate *s*² through which passes the pivot pin *f*³ connecting the forward transverse stretcher *f* with the footboard *g*.

Moreover, as shown in Fig. 11 a stay 20 socket or step *u* may be fitted to one of the forward diagonal struts *e* to receive the mast *t* and the socket or step may also if desired be temporarily fixed by a screw or 25 clips to the foot board *g* in any convenient manner.

Or as shown in Figs. 12 and 13, the foot of the mast may rest in a step or socket *u*¹ fixed to one of the diagonal struts *e* and auxiliary struts *v* may be provided between 30 and each is suitably hinged to the upper end of each of the forward diagonal struts *e* and the mast *t*. Also stay ropes may be connected with the mast and eyes secured to the fabric or to the stiffeners *c* at the nose 35 and at the quarters of the boat as will be readily understood without illustration.

When the foot board *g* is removed in collapsing the boat, the second and third stretchers *f* are partially rotated as shown 40 in Fig. 14 so that the ends of these stretchers do not project beyond the edges of the foot-board, but if the terminal or first and fourth stretchers *f*³ are rigid they will extend at the ends of the sides of the foot 45 board. In order, however, to permit of these terminal stretchers being contained within the confines of the foot-board they are each divided into halves and hinged in the middle on the pivot *f*¹ on which the stretcher is 50 adapted to be partially rotated. This construction differs from that shown in Figs. 1 and 2 inasmuch as there are only four stretchers on floors *f* instead of five and all 55 four stretchers are pivoted to the foot-board.

As shown in Figs. 15 and 16 there are three side stiffeners or canes *c* *c*³ and *c*⁴ on each side of the boat, these canes being bent to produce a cross section of ordinary boat 60 shape and the two uppermost canes *c* are conveniently inserted in tubular pockets *d* along the gunwales. If desired the stiffeners *c*³ may also be inclosed in similar pockets. Beneath the floor board there are three 65 stiffeners *c*⁴ *c*⁴ and *x*, the one marked *x*,

being a keelson or keel stiffener which lies along a keel rod *y* inclosed in a pocket *a*² of the skin *a* of the boat and the other two (*c*⁴) are adapted to impart the desired shape to the bottom of the boat below the foot-board *g*. If desired, these canes may be inserted within tubular pockets integral with the skin of the hull. 70

In this case, some of the stretchers *f* may be pivoted to the floor boards *g* at *f*¹ and others may be separate and the keel stiffener *x* is conveniently pressed downward by strut devices *x*¹ inserted between these loose stretchers *f* and the keel stiffener *x*. Or the strut devices *x*¹ may be hinged to stretchers 80 *f* at *x*².

Or as shown in Figs. 17 and 18, the strut devices may each consist of a small piece of wood *x*³ hinged at *x*⁴ to the stretcher *f* and furnished with a shaped wire spring *x*⁵ 85 adapted to elastically engage with the keel stiffener *x*.

As shown in Fig. 19 the ends or end portions of the longitudinal stiffener rods or canes may be connected together by a U-shaped wire *z*¹ of metal (see also Figs. 15 and 16) which wire may be suitably engaged with the holes in the canes instead of using the rope or cord *z* already referred to in some of the previous figures, such as Figs. 95 1, 2 and 3, and so that, in this particular case, the bottom part of the U-shaped wire engages the keel or stiffener *x* and the lower canes *c*⁴, while the ends of the limbs of the U pass through the other stiffeners. A cross 100 piece or wire *z*² formed with a loop at each end or a short piece of metal plate perforated at each end is passed over the two extremities of the said limbs, which latter are conveniently provided with screw threads at 105 their ends. Nuts *z*³ are then screwed down upon the ends of the U-shaped wire and on to the loops or eyes of the cross wire between the gunwale stiffeners or canes and the nuts, the loops or perforated plates acting as 110 washers. The nuts are adjusted until the U-shaped wire is drawn through the gunwale stiffeners to the desired extent for holding all the stiffeners in the desired relative positions. By this mode of securing 115 the stiffeners, the latter are held rigidly in position without possibility of twisting, and, nevertheless, the boat may be collapsed as readily as when cords are employed. In a 120 flat bottomed boat only the stiffeners or canes on respective sides are passed over respective limbs of the U-shaped wire. The U-shaped wires may be applied to the stiffeners quite close to the ends thereof and the nuts may, when tightened up, squeeze one stiffener upon another with or without the interposition of washers or other packing material.

I claim:

1. A collapsible boat comprising a skin of flexible waterproof material, a pocket at 130

each end of said skin, a plurality of flexible longitudinal ribs connected together at their ends and engaging in the said pockets, means for connecting the longitudinal ribs to the skin intermediate of their ends, a plurality of transverse stretchers for distending one pair of the said ribs to form the angle at the junction of the sides and the bottom of the boat, a plurality of cross-ties for connecting the ribs together and, toward each end of the boat, a pair of crossed diagonal struts, connected together, each engaging at one end with an upper longitudinal rib, on one side and at the other end with a lower longitudinal rib on the other side of the boat.

2. A collapsible boat comprising a skin of flexible waterproof material, a pocket at each end of said skin, a plurality of flexible longitudinal ribs connected together at their ends and engaging in the said pockets, means for connecting the longitudinal ribs to the skin intermediate of their ends, a plurality of transverse stretchers for distending one pair of the said ribs to form the angle at the junction of the sides and the bottom of the boat, a plurality of cross-ties for connecting the ribs together, a plurality of intermediate longitudinal stiffeners between the ribs forming the gunwales and the ribs at the junction of the sides and bottom and, toward each end of the boat, a pair of crossed diagonal struts, connected together, each engaging at one end with an upper longitudinal rib, on one side and at the other end with a lower longitudinal rib on the other side of the boat.

3. A collapsible boat comprising a skin of flexible waterproof material, a pocket at each end of said skin, a plurality of flexible longitudinal ribs connected together at their ends and engaging in the said pockets, means for connecting the longitudinal ribs to the skin intermediate of their ends, a plurality of transverse stretchers for distributing one pair of the said ribs to form the angle at the junction of the sides and the bottom of the boat, a plurality of cross-ties for connecting the ribs together, a plurality of struts to force apart the upper pair of ribs forming the gunwales and the ribs at the junction of the sides and bottom, and, toward each end of the boat, a pair of crossed diagonal struts, connected together, each engaging at one end with an upper longitudinal rib, on one side and at the other end with a lower longitudinal rib on the other side of the boat.

4. A collapsible boat comprising a skin of flexible waterproof material, a pocket at each end of said skin, a plurality of flexible longitudinal ribs connected together at their ends and engaging in the said pockets, means for connecting the longitudinal ribs to the skin intermediate of their ends, a plurality of transverse stretchers for distribut-

ing one pair of the said ribs to form the angle at the junction of the sides and the bottom of the boat, a plurality of cross-ties for connecting the ribs together, a plurality of struts to force apart the upper pair of ribs forming the gunwales and the ribs at the junction of the sides and bottom, a plurality of inclined struts each mounted between and engaging one of the upper pair of ribs and a stretcher at a place intermediate of its ends, and, toward each end of the boat, a pair of crossed diagonal struts, connected together, each engaging at one end with an upper longitudinal rib, on one side and at the other end with a lower longitudinal rib on the other side of the boat.

5. A collapsible boat comprising a skin of flexible waterproof material, a pocket at each end of said skin, a plurality of flexible longitudinal ribs connected together at their ends and engaging in the said pockets, means for connecting the said ribs to the skin intermediate of their ends, a plurality of transverse stretchers for distending one pair of ribs to form the angle at the junction of the sides and the bottom of the boat a plurality of pairs of crossed diagonal struts, pivoted together, each diagonal strut engaging at one end with an upper rib on one side and at the other end with a lower rib on the other side of the boat, a plurality of ties for connecting together the upper pair of ribs and a plurality of ties for connecting together the lower pair of ribs.

6. A collapsible boat comprising a skin of flexible waterproof material, a pocket at each end of said skin, a plurality of flexible longitudinal ribs connected together at their ends engaging in the said pockets, means for connecting the said ribs to the skin intermediate of their ends, a plurality of transverse stretchers for distending one pair of ribs to form the angle at the junction of the sides and the bottom of the boat a plurality of pairs of crossed diagonal struts, pivoted together, each diagonal strut engaging at one end with an upper rib on one side and at the other end with a lower rib on the other side of the boat, a plurality of struts to force apart the upper and lower ribs on each side of the boat, a plurality of ties for connecting together the said upper and lower ribs, a plurality of ties for connecting together the upper pair of ribs and a plurality of ties for connecting together the lower pair of ribs.

7. A collapsible boat comprising a skin of flexible waterproof material, a pocket at each end of said skin, a plurality of flexible longitudinal ribs connected together at their ends and engaging in the said pockets, means for connecting the said ribs to the skin intermediate of their ends, a plurality of transverse stretchers for distending one pair of ribs to form the angle at the junc-

tion of the sides and the bottom of the boat, a plurality of pairs of crossed diagonal struts, pivoted together, each diagonal strut engaging at one end with an upper rib on 5 one side and at the other end with a lower rib on the other side of the boat, a plurality of struts to force apart the upper and lower ribs on each side of the boat, a plurality of ties for connecting together the upper 10 and lower ribs, a plurality of inclined struts, each mounted between and engaging an upper rib and a stretcher at a place intermediate of its ends, a plurality of ties for connecting together the upper pair of ribs and 15 a plurality of ties for connecting together the lower pair of ribs.

8. A collapsible boat comprising a skin of flexible waterproof material, a pocket at each end of said skin, a plurality of flexible 20 longitudinal ribs connected together at their ends and engaging in the said pockets, means for connecting the said ribs to the skin intermediate of their ends, a plurality of transverse stretchers for distending one 25 pair of ribs to form the angle at the junction of the sides and the bottom of the boat, foot boards adapted to rest on the said stretchers, a plurality of pairs of crossed diagonal struts, pivoted together, each diagonal strut 30 engaging at one end with an upper rib on one side and at the other end with a lower rib on the other side of the boat, a plurality of ties for connecting together the upper pair of ribs and a plurality of ties for connecting together the 35 lower pair of ribs.

9. A collapsible boat comprising a skin of flexible waterproof material, a pocket at each end of said skin, a plurality of flexible longitudinal ribs connected together at their 40 ends and engaging in the said pocket, means for connecting the said ribs to the skin intermediate of their ends, a plurality of transverse stretchers for distending one pair of ribs to form the angle at the junction of the sides and the bottom of the boat, some 45 of the said stretchers being pivoted to foot boards, the said foot boards, adapted to rest on the stretchers, a plurality of pairs of crossed diagonal struts, pivoted together, 50 each diagonal strut engaging at one end with an upper rib on one side and at the other end with a lower rib on the other side of the boat, a plurality of ties for connecting together the upper pair of ribs and a 55 plurality of ties for connecting together the lower pair of ribs.

10. A collapsible boat comprising a skin of flexible waterproof material, a pocket at each end of said skin, a plurality of flexible 60 longitudinal ribs connected together at their ends and engaging in the said pockets, means for connecting the said ribs to the skin intermediate of their ends, a plurality of transverse stretchers for distending one pair of 65 ribs to form the angle at the junction of the

sides and the bottom of the boat, some of the said stretchers being pivoted to foot boards intermediate of and in the neighborhood of the ends of the foot boards, the stretchers near the ends of the foot boards 70 being divided in the middle and hinged so as not to project beyond the edges of the foot boards except when in the extended condition, the said foot boards, adapted to rest on the stretchers, a plurality of pairs of 75 crossed diagonal struts pivoted together, each diagonal strut engaging at one end with an upper rib on one side and at the other end with a lower rib on the other side of the boat, a plurality of ties for connecting together 80 the upper pair of ribs and a plurality of ties for connecting together the lower pair of ribs.

11. A collapsible boat comprising a skin of flexible waterproof material, a pocket at 85 each end of said skin, a plurality of flexible longitudinal ribs connected together at their ends and engaging in the said pockets, means for connecting the longitudinal ribs to the skin intermediate of their ends, a plurality 90 of transverse stretchers for distending one pair of the said ribs to form the angle at the junction of the sides and the bottom of the boat, a plurality of cross-ties for connecting the ribs together, cleats on the said ribs to 95 retain the stretchers and struts in position, and, toward each end of the boat, a pair of crossed diagonal struts, connected together, each engaging at one end with an upper longitudinal rib, on one side and at the other 100 end with a lower longitudinal rib on the other side of the boat.

12. A collapsible boat comprising a skin of flexible waterproof material, a pocket at each side of the said skin, a buoyant cushion 105 in each pocket, a pocket at each end of said skin, a plurality of flexible longitudinal ribs connected together at their ends and engaging in the end pockets, means for connecting the longitudinal ribs to the skin intermediate of their ends, a plurality of transverse stretchers for distending one pair of the said ribs to form the angle at the junction of the sides and the bottom of the boat, a plurality 110 of cross-ties for connecting the ribs together, and, toward each end of the boat, a pair of crossed diagonal struts, connected together, each engaging at one end with an upper longitudinal rib, on one side and at the other 115 end with a lower longitudinal rib on the other side of the boat.

13. A collapsible boat comprising a skin of flexible waterproof material, a pocket at each end of said skin, a plurality of flexible longitudinal ribs connected together at their 120 ends and engaging in the said pockets, means for connecting the longitudinal ribs to the skin intermediate of their ends, a plurality of transverse stretchers for distending one pair of the said ribs to form the angle at the 125

junction of the sides and the bottom of the boat, a plurality of cross-ties for connecting the ribs together, a keel rod, a longitudinal pocket in the skin to contain said rod, a keel stiffener adapted to press on the said rod, struts mounted between the stretchers and the keel stiffener, and, toward each end of

the boat, a pair of crossed diagonal struts, connected together, each engaging at one end with an upper longitudinal rib, on one side and at the other end with a lower longitudinal rib on the other side of the boat.

ARCHIBALD EDWARD FORD.
